APPARATUS FOR RECORDING RESPIRA-
TORY AND CIRCULATORY CONDITIONSThomas Bradford, Chicago, Ill., assignor to
William J. Cameron, Chicago, Ill.

Application December 31, 1936, Serial No. 118,565

7 Claims. (Cl. 128—2.05)

My present invention relates to an apparatus for indicating and recording conditions occurring in both the respiratory and the circulatory system of the human body. With the present apparatus the attendant or operator may readily determine the systolic and diastolic pressures of a person under examination, the rhythm of the heart beat and the characteristics of the pulsations. Furthermore, the operator may ascertain the rhythm of inhalation and exhalation and the characteristics thereof. Also the attendant, during the ascertaining of the aforesaid conditions may definitely record them upon a single chart or graph-sheet in order that these conditions may be studied for the purpose of diagnosis and the chart thereafter kept as a permanent record of the particular patient. In ascertaining conditions of both the circulatory system and the respiratory system visual means are provided, preferably in the form of an illuminated lamp or target in order that the operator need not depend upon the use of a stethoscope.

Abnormal conditions occurring in the respiratory system of a patient frequently influence the determination of conditions in the circulatory system, and it sometimes transpires that while blood pressures and heart beats of a particular patient are being recorded the patient may either inadvertently or intentionally, retard or increase his respiratory actions. When these conditions are present there is a consequent abnormal change in the circulatory system. For example: if a patient, during the transcribing of a record of his heart beats or pulse should intentionally hold his breath there is an immediate retardation of the rhythm and the characteristics of the heart beats. With the present apparatus I have arranged the structure so that the record or graph made in recording the blood pressures and heart beats is alongside and parallel with the recorded graph of the respiratory system so that it is definitely co-ordinated therewith to such an extent that the physician making the record or the examination will be able to immediately determine whether the abnormality noted in the circulatory graph has been caused by an abnormality occurring in the respiratory system during the recording of the heart graph. It will be apparent this is of vital importance in securing an accurate record of a patient's heart and circulatory conditions. Provision is made in the present apparatus for charting auricular conditions through the medium of the jugular at the patient's neck. This permits the physician to note auricular abnormalities which may not

appear on other portions of the chart or graph-sheet because of the fact that the record of the diastolic pressure is subject to influence by the contraction of the left ventricle of the heart.

The apparatus which I have devised is enclosed within a small cabinet so that it is readily portable and may be carried from one location to another by the physician. The present structure is therefore considerably less cumbersome than the large devices and apparatus which are usually installed in examination rooms of hospitals, sanitariums and similar places.

One of the objects of my present invention is to provide an apparatus that is readily capable of operating in the manner herein set forth to accomplish the purposes for which it has been designed and to do this in an effective and dependable manner. Other objects are to provide an apparatus of this character that is novel in construction; dependable in operation; compact in the design and assemblage of the parts comprised in its make-up; easy to manipulate and operate; simple and sturdy in the formation of the parts so that it will not readily get out of order; and which is economical to manufacture so that it may be sold to the user for a reasonable retail price. Numerous other objects and advantages will be apparent to persons skilled in the art after the construction and operation of my apparatus is understood from the following disclosure.

I prefer to accomplish the numerous objects of my invention and to practice the same in substantially the manner hereinafter fully described and as more particularly pointed out in the appended claims. The accompanying drawings are referred to for better understanding of the construction and operation of my apparatus.

In the drawings:

Figure 1 is a vertical front elevation of the apparatus with the front wall or door opened or removed.

Figure 2 is a vertical elevation, partly in section on the plane of line 2—2 of Figure 3.

Figure 3 is a top plan of the structure shown in Figure 2 looking at the parts in the plane of line 3—3 thereon.

Figure 4 is a vertical transverse section taken on line 4—4 of Figure 1 looking to the left in the direction of the arrows.

Figure 5 is a detail, in horizontal section, of one of the devices for individually disengaging a pointer-pen from the graph-sheet or chart.

Figure 6 is a cross sectional detail of the re-winding roller for the graph-sheet or chart.

Figure 7 is a graphic illustration showing the manner of using the apparatus and applying certain of the parts to portions of the human body.

5 Figure 7a is a vertical axial section of one of the clutch devices that is used in this apparatus.

The mechanism is housed within a carrying case or cabinet consisting of removable front or door A, the latter being mounted by hinges B 10 on the box-like body, the door being provided with an opening in which a glass panel C is mounted. A base D supports the body, which latter consists of the rear wall E, side walls F, and top G. There is a rectangular plate H that 15 is suitably mounted in the case to provide a main support that is spaced from the rear wall, and brackets I project from supporting plate H to mount a vertically disposed platen or bed J back of the door. The operating mechanism is preferably mounted upon the plate H in the manner 20 hereinafter described so that the plate may be removed with the mechanism without necessarily disturbing the latter.

The platen or bed J is in a plane back of and 25 spaced from the glass plate C extending across the opening in the door as seen in Fig. 4 and provides a flat bed across which the graph-sheet 5 travels in the manner presently to be described. The graph-sheet 5 is preferably a continuous strip of paper which unwinds from a supply roll 6 that is wound upon a core 7 and the ends of the core are provided with trunnions 8 that are removably mounted in vertically disposed bearing slots 9 in the upper edges of spaced 30 brackets 10 secured to the lower portions of the support H. After leaving the supply roll the graph-strip passes upward and over a driving roller 11 that is supported by threaded pintles 12 adjustably screwed into horizontal threaded 35 apertures at the ends of spaced brackets 13 and 14 secured to and projecting from an upper portion of the supporting plate H. Lock-nuts 15 maintain the pintles in their adjusted positions. The marginal portions of the graph-sheet are 40 provided with continuous rows of perforations a and b that are engaged by sprocket-pins 11a and 11b projecting radially from end portions of the driving roller 11 to insure the positive drive of the continuous strip. After passing off 45 the roller 11 the graph-sheet 5 moves downward across the platen J to a re-wind roller 16 that extends horizontally across the structure near the bottom of the cabinet or casing. One end of the re-wind roller 16 is supported by a 50 threaded pintle 17 that is adjustably screwed into a horizontal threaded aperture in the end of the adjacent bracket 10, and a lock-nut 18 holds the pintle in adjusted position. The other end of the re-wind roller is supported by a 55 spring-actuated retractable plunger 19 mounted in the adjacent bracket 10 and having a finger grasp 20 by which it may be manipulated. In order to dependably anchor the lower end 60 edge of the graph-sheet 5 to the re-wind roller 16 the latter is preferably split longitudinally to provide separable members consisting of a longitudinal semi-cylindrical body portion 16a and a longitudinal toric segment 16b, both of which have flat opposing faces, and one of said members 65 is provided with a plurality of short studs 16c that puncture the graph-sheet 5 and enter sockets 16d in the other member as illustrated in Fig. 6.

Suitable actuating mechanism is provided for 70 driving the rollers 11 and 16, which said mech-

anism embodies a small electric motor 21, one end of its spindle carrying a fan 22 for cooling it and the other end of its spindle operatively connected to a suitable speed-reducer unit 23. The motor and reducer unit are suitably connected together and secured to an adjacent portion of the near-by bracket I that supports the platen. A driven element 24 of the reducer projects out of the side of its housing opposite the motor and has a beveled or worm gear 25 secured to it that is in mesh with and actuates a beveled or worm gear 26 fast on the intermediate portion of a vertical shaft 27. There are vertically aligned bearings 28 for shaft 27 above and below the gear 25, and other bearings 29 and 30 respectively for the upper and lower end portions of the shaft. Above the upper bearing 29 the shaft 27 has a worm gear 31 secured to it that meshes with a worm gear 32 secured to the adjacent end portion of the roller 11 to drive the latter in the proper direction to unwind the graph-sheet 5 from the supply roll 6 and move said sheet downward. A worm gear 33 is secured to the lower portion of the shaft 27 above the bearing 30 and a worm gear 34 at the end 25 of the re-wind roller 16 meshes therewith and is driven thereby. Thus the two rollers 11 and 16 are moved in unison. The gear 34 on the re-wind roller however is not fast on the roller 16 but it is frictionally mounted thereon to permit of a proper amount of slippage which may be necessary on account of the fact that the winding of the strip upon the roller 16 will progressively or gradually increase the over-all diameter of the roller and accumulating windings of 30 the sheet.

There are a plurality of inscribing pointers that are actuated by independent mechanisms, each of which is under the influence of a pressure-responsive or pressure-sensitive element. 40 These pointers are identified by the characters X, Y and Z, and since, for the purposes of economy, they are all of the same general construction, only one of them will be described. A pointer embodies an elongated strip of light 45 flexible metal having keyholes in its upper end portion to removably mount it pendently upon headed studs 35 projecting from a carrier 36 that is swingingly connected by a pintle 37 to a U-shaped yoke 38 that has a small friction 50 tube 39 projecting rearward from its horizontal connecting member so that the pointer may be readily and removably mounted in a frictional manner upon the end of an actuating spindle that is adapted to swing the pointer. A cylindrical spring holder 40 is formed at the lower 55 free end of the pointer to removably receive the body of a fountain stylus 41 the point or nib of which is adapted to be engaged with the outer surface of the graph-sheet when the pointer is 60 in its operative position to inscribe the chart.

The pressure-responsive or pressure-sensitive elements which provide the movement or power for actuating the pointers are in the form of a corresponding number of bellows or like elements 65 x, y and z that have movement transmitting and movement amplifying devices operatively connecting them with the respective pointers X, Y and Z.

The bellows x is for operation under the influence of low pressures and pulsating pressures and the bellows y is for operation under the influence of high pressures, said bellows being separably employed for ascertaining and recording systolic and diastolic blood pressures of a patient, 70 75

and one of these structures is utilized for ascertaining and recording the heart-beats or pulsations as well as the character of the latter. Pressure fluid for bellows x and y is received from the source through a hose 42 connected to the end of a pipe 43 projected out through a wall of the cabinet. The pipe leads to and communicates with one end of the longitudinal bore or passageway of a T-shaped coupling 44 the opposite end of which coupling communicates with a pipe 45 leading to and discharging into the bellows x . The lower head of bellows x has a depending hollow stub 46 that is externally threaded to screw into a bracket 47 projecting from the main support H and is suitably anchored in place preferably by adjustable lock-nuts 48. The upper head of the bellows x has an axial guide-rod 49 secured to it that extends up through a bearing or guide bracket 50 also mounted on and projecting from the supporting plate H .

Suitable mechanism for transmitting and amplifying the movement of the bellows and guide-rod 49 operatively connect said rod to a horizontal rock-spindle 51 that carries the pointer arm X . The upper portion of the the rod 49 has an elongated rectangular block 52 detachably connected to it by means of friction clutch elements in the bottom of the circular bore 53 of said block. Near its lower end the bore is reduced to provide a conical seat 54 for a fiber friction member 55 that is bored and split and has a cone-shaped lower end to engage the seat 54. A rotatable operating tube 56 surrounds the rod and projects out of the block through an opening 57 in the top G of the cabinet where its end is provided with a headed finger-grip 58. Near its center of length the tube has a widened portion 59 that is provided with threads to engage threads 60 in the adjacent portion of the bore 53. A coiled expansion spring 61 surrounds the rod 49 between the clutch cone 55 and the lower end of the tube 56 and suitable washers 62 surround the rod at the lower end of the tube and the top of the clutch cone. A set-screw 52a, set transversely in the block, enters a longitudinal groove 49a in the guide-rod and permits relative longitudinal movement of the block and rod but prevents rotation of one with respect to the other. To operate the clutch, the block 52 is held stationary by moving a forked slide 9 on top of the cabinet into slots 9' on opposite sides of the block and the tube 56 is rotated by its finger-grip 58 which causes the spring 61 to wedge the cone 55 down into its seat 54, after which the slide is withdrawn. Reverse rotation of the tube releases the clutch which is assisted by a split spring ring 63 that is imbedded annularly in the cone.

When the rod 49 has been clutched to the block 52 it becomes operatively connected to the movement transmitting and amplifying mechanism and actuates the rock spindle 51 carrying the pointer arm x so that any movement (even very slight) of the bellows and guide-rod is amplified to a substantial extent and is recorded at the free end of the pointer X upon the graph-sheet.

The movement transmitting and amplifying devices are mounted in a frame consisting of two laterally spaced vertical plates 64 and 65 that are supported from plate G by horizontal posts 66, and the rod 49 and block 52 extend into and through this frame. A short forked arm 67 is secured to a face of the block with its bifurcation 75 projecting beyond the same, and a horizontal

rocker-shaft 68 extends between and is journaled in plates 64 and 65 parallel with the spindle 51. This rocker-shaft has an elongated collar 69 secured to it with a short lateral lever-arm 70 projecting radially from one end alongside the fork 67, and said lever-arm has a longitudinal slot 71 in which a transverse pin 72 is adjustably mounted in a position to enter and engage the fork 67. An elongated lever-arm 73 is connected intermediate its ends to the other end of the collar 69 and is disposed so that its outer (right) end projects between the adjacent pair of posts 66 and its inner (left) end extends towards the block 62 where it has a forked member 14 adjustably secured to it by clamp 15 screws. Up and down oscillation of the lever-arm 73 is limited and regulated by means of adjustable stops in the form of set-screws 75 threaded transversely through the adjacent upper and lower posts 66. The fork member 14 is engaged with a cam-pin 76 adjustably carried in a slotted arm 77 projecting radially from a small sleeve 78 fast on the rocker spindle 51 which has bearings in the plate 64 and 65 of the frame. Thus, whenever the pressure moves bellows x , or causes it to fluctuate (pulsate), such movement or pulsation is definitely transmitted to the pointer arm X in amplified form to be accurately and permanently recorded upon the graph-sheet.

The visual means for indicating the movement or operation of the bellows x embodies side-by-side electric lamps 79 and 80 of different colors (preferably of neon gas type) that are supported in spring clips back of windows in the front of the cabinet. The current to the lamps passes through a transformer 81 which reduces the alternating service current of 110-v. to a low amperage such as is utilized for operating neon gas lamps.

The guide rod 49 of the low-pressure bellows x has a collar 82 adjustably secured to it between the bellows and the guide bracket 50, which said collar has an extension 83 that is provided with a transverse pin 84. Alongside the bearing bracket 50 there is a frame consisting of vertical plates 64 and 65 that are laterally spaced from each other and supported by the reduced portions of posts 81 that project horizontally from the supporting plate H . The compositely formed walking-beam lever arm is fulcrumed intermediate 50 its ends upon a rock-pin 88 that is horizontally disposed between the plates and is journaled therein. A portion 89 of this arm is an insulating bar that extends toward the collar 82 on the guide rod and at its free end there is a fork 55 or bifurcated plate 90 that is adjustably maintained upon the adjacent end of said insulating bar by set screws 91 so that the slotted portion of said fork is engaged with the pin 84 and said arm is rocked thereby whenever the guide rod 49 is moved up or down to the slightest extent. The other end of the lever arm just described has a gear segment 92 secured to it with its teeth engaged with a small pinion 93 on a spindle 94 that has bearings in the frame platen 85-86. 65 One end of the spindle 94 (preferably the end towards the cabinet door) extends through the frame plate 85 and has a small disk 95 secured to it. The edge of this disk has a shallow groove that provides an annular friction seat for an oscillating contact-forming wire arm 96 that is substantially vertically disposed and extends upward to near the top of frame plate 85 where it is provided with a contact block 97.

A substantially U-shaped contact carrier 98 is 75

secured to the frame plate 85 and is insulated therefrom, and said carrier is located in a position so that its lateral arms extend outwardly away from the frame plate upon each side of the contact block 97 just mentioned. Small pin-point contacts 99 and 100 are carried in the facing portions of the arms of carrier 88 and are adjustably spaced apart a distance sufficient to allow the block 97 to move or vibrate between them and engage with one and then with the other at each end of its movement. A conductor wire 101 leads from a source of current supply to the screw which anchors the U-shaped carrier 98 to the frame plate. The oscillating spring 10 contact arm 96 and the pin-point contacts 99 and 100 provide a circuit interrupter or make-and-break device that is quite sensitive and is operated upon the slightest movement of the bellows α . The lower end portion of the wire forming the 15 oscillating arm 96 is bent into the shape of a flat spring loop 102 and next to this loop the wire is bent into opposing right-angle shapes 103 that combine to form a small square the diagonally opposite halves of which are yieldably urged 20 toward each other by the spring loop 102. The sides of the rectangle 103 tangentially engage in the edge groove of the rotatable disk 95 and are maintained therein by the friction between the parts, such friction being sufficient to permit the 25 arm and the disk to be moved together in one direction a slight distance until the embossment 97 engages one or the other of the pin-point contacts 99, 100. After a contact has been engaged by the embossment 97, the disk 95, by 30 overcoming the friction, will continue its rotative movement in one direction independently of the wire rectangle of the arm 96 but the arm will remain stationary until the disk has changed its direction of rotation whereupon the disk will 35 swing the arm 96 in a reverse direction so that the embossment 97 leaves one pin-point contact and engages the other thereof. An upward movement of the guide rod 49 causes the disk 95 to be rotated clockwise to swing the spring 40 contact arm 96 to the right hand pin-point contact 100 and downward movement of the guide rod swings the arm 96 to the left hand pin-point contact 99.

When the bellows has been inflated so that it 45 responds to pulsating pressures, these pulsations, although they may be very slight, cause a rapid to and fro vertical movement of the fork 80 and arm 89, and this vibratory movement is transmitted in amplified form to the contact forming 50 arm 96 which causes a rhythmic movement of said arm 96 so that it touches one and then the other of the contacts 99 and 100 and thereby causes an alternative flashing of the neon lamps. So long as this rhythmic flashing of the lamps continues 55 the physician or attendant is definitely aware of the presence of a pulsating pressure within the pneumatic system, and when the pressure has been increased or diminished to a degree where pulsations cease to be observed the vibratory 60 movement of the contact forming arm 96 will cease and the embossment 97 thereon will come to rest while engaged with one or other pin-point contacts 99, 100 with the result that the lamps will cease their alternate flashing and only one 65 lamp will continue to burn in steady illumination while the other lamp will have been extinguished. Under this latter condition the operator will be aware of the fact that a critical point of pressure 70 has been reached and pulsating pressure has ceased.

The pointer Y is actuated by the high pressure bellows γ which latter element receives the pressure fluid through a pipe 104 connected at one end to and communicating with said bellows and at its other end leading to the lateral stub 105 of the T-shaped coupling 44. The lower head of the bellows γ extends through a suitable bracket 106 that is mounted upon the supporting plate H and the upper head of the bellows carries an axial guide rod 107 that extends upwardly 10 and is freely engaged in a bearing bracket 108 projecting from the upper portion of supporting plate H. A light expansion spring 109 surrounds the guide rod between bracket 108 and the upper head of the bellows. At the upper end of the 15 guide rod above the bracket 108 there is a transversely disposed disk 110 that is securely anchored thereon by a set screw, and slightly above and at one side of the disk 110 there is a horizontally disposed rock-spindle 111 that is long enough to 20 extend through the bearing in the bracket 108 and protrude forwardly therefrom to a point above the platen J where it receives the friction sleeve 39 on the articulated or hinged portion of the indicator or pointer arm Y. An elongated 25 sleeve 112 is anchored to the rock-spindle 111 and has a spherically headed member 113 projecting laterally or radially therefrom in a slightly inclined or oblique direction downwardly into the contact of the upper face disk 110 at the upper 30 end of the guide rod. When the bellows is inflated the upward movement of its guide rod 107 causes the member 113 to rock the spindle 111 and correspondingly move the pointer arm Y. In order to insure return movement of the rock-spindle a light coiled spring 114 surrounds such 35 spindle and has one end anchored thereto or to the collar 112 while its other end is anchored to or engaged with an adjacent portion of the bearing bracket.

The pressure creating means is preferably in the form of an elastic bag 115 enclosed in a pocket within an elongated fabric ribbon or band 116 that is usually wrapped about the patient's arm above the elbow. The hose 42 communicates 40 with this bag and another hose 117 leads from the bag to a manually operated collapsible bulb 118 that has a control valve 119 and an automatic inlet port 120. The arm band in its usual application is across the brachial artery so that pulsations or heat beats of the patient will be transmitted to the low-pressure bellows α . During the time the low-pressure bellows α responds to pulsations, the neon lamps or indicators will alternately flash due to the vibratory movement 45 transmitted to the oscillating arm 96 by the fluctuations of the bellows α . If the physician or attendant continues to inflate the bag 115 of the arm-band to a point where the brachial artery is completely collapsed the critical point 50 of high pressure or systolic pressure will be indicated by cessation of the alternate flashing of the lights and such pressure may then be recorded upon the graph-sheet by the pointer arm Y by starting the motor 21 to move the chart sheet 55 a short distance to mark a graph line. The motor is then turned off to stop movement of the graph sheet for the next stage of recording. To ascertain low diastolic pressure the elastic bag is deflated rapidly by manipulating the control 60 valve 119 to exhaust a portion of the pressure fluid. During this deflation the lights will continue to alternately flash. When the pressure has been reduced to a point where the lights 65 cease to alternately flash and one bulb remains 70 75

illuminated the physician or attendant is then aware of the fact that the critical point of low or diastolic pressure has been reached and the motor may be again started to record such pressure upon the moving graph-sheet by means of the pointer arm X.

The hollow lower head of bellows z which operates the pointer Z extends through a bracket 121 projecting from the supporting plate G and is held in position by lock-nuts 122 and the pressure fluid is fed to this bellows through a pipe 123 the other end of which is projected out through a wall of the cabinet. A hose 124 leads from the projected end of pipe 123 to and communicates with the interior of an inherently elastic pneumograph 125 that embraces the chest or abdomen of the patient. Details of construction of the pneumograph are not shown as such devices are quite well-known and in general use. Briefly described, the pneumograph consists of a long spiral spring covered with a flexible rubber tube and both the spring and the tube attached to lateral bosses on end plates in a manner to make the arrangement air-tight. The end plates have means in the form of headed pins for a chain that is used to adjust the structure taut around the chest or abdomen of the patient, and one of these bosses has a small hollow stub for establishing communication between the pneumograph and the hose 124. Thus, expansion and contraction of the chest or abdomen due to inhalation and exhalation will respectively elongate and retract the elastic portion of the pneumograph and cause expansion and contraction of the bellows z. Thus the respiratory movements may be readily recorded on the graph-sheet by the pointer arm Z.

The portion of the apparatus which is operated in connection with a patient's respiratory system is quite valuable not only in ascertaining the volume of inhalation and exhalation and the rhythm of these respiratory acts, but it is equally useful in determining some of the underlying causes of abnormalities that may have been noted in the circulatory system. It likewise is valuable in showing the influence on the heart action of retardation of inhalation or exhalation that may have been either intentional or inadvertent on the part of the patient. In order that accurate comparisons may be made, a respiratory record is therefore delineated upon the graph-sheet simultaneously and synchronized with and in a longitudinal parallel zone alongside a record or records made of the circulatory system. Thus, the readings of the respiratory system and the circulatory system are coordinated upon a single graph-sheet. The recording of the respiratory graph is accomplished by pointer Z through the transmitting amplifying mechanism operatively connecting the bellows and pointer which will now be described.

The upper head of the bellows z has a vertical guide rod 126 that extends through a bearing bracket 127 and has an elongated block 128 connected to it by means of a clutch device similar to the device upon the upper portion of the guide rod 49 of the low pressure bellows x, and which therefore need not be here described. It will be noted however that the operating finger-piece 129 of the clutch in block 128 does not protrude through the wall of the cabinet since this clutch is adapted to be adjusted at the factory during calibration of the apparatus and is not later manipulated or tampered with by the user.

Adjacent the block 128 there is a frame consisting of laterally spaced vertical plates 130 and 131 that are supported on horizontal posts 132 projecting from the main plate G, and a horizontal rock-spindle 133 is journaled in these plates with its forward end extended to the vertical plane of the platen J to receive the friction sleeve 39 of the pointer Z. A short forked arm 134 is secured to a side face of block 128 and a horizontal rocker-shaft 135 is journaled in plates 130-131 parallel to rock-spindle 133 with an elongated collar 136 secured to it. The forward end of this collar carries a short lever-arm 137 that projects radially alongside forked arm 134 and has a longitudinal slot to adjustably receive 15 a transverse pin 138 that is engaged between the fingers of the fork 134. At the rear end of the collar 136 an elongated lever-arm 139 is connected thereto so that its right end portion vibrates between the adjacent posts and has its 20 movement limited and regulated by adjustable stops 140. The inner left portion of lever-arm 139 extends towards rock-spindle 133 and has a forked plate 141 adjustably secured to it that has its slotted portion engaged with a trans- 25 verse pin 142 adjustably carried in the adja- cent portion of a short arm 143 that projects from a small sleeve 144 adjustably secured on and movable with the rock-spindle 133 which 30 actuates the pointer Z. In this manner the up 35 and down movement of the bellows z is definitely transmitted to the pointer Z in an amplified manner and may be recorded on the graph-sheet to delineate the respiration of the patient.

In connection with the respiratory actions of the patient I have provided devices for visually indicating the inhalations and exhalations through the medium of lights or illuminated targets. These devices preferably embody a pair of side-by-side neon gas lamps 145 and 146 of dif- 40 ferent colors that are mounted back of windows in the front of the cabinet, and the current to these lamps passes through a transformer 147 similar to and for the same purpose as the previously described transformer 81. Alongside the 45 frame supporting the respiratory mechanism there is another frame embodying laterally spaced vertical plates 148 and 149 supported from the back plate G by horizontal posts 150. Journaled in these plates is a rotary spindle 151 carrying 50 a pinion 152 and the forward end of this spindle protrudes through plate 148 and has a small edge-grooved disk 153 secured to it. The groove in the disk provides an annular friction seat for a vibratory contact-forming wire arm 154 55 that depends vertically therefrom and near its lower end the wire has a contact block 155 secured to it that operates between the lateral arms of a U-shaped contact carrier 156 that is insulated from the frame plate 140. The arms of the 60 carrier 156 adjustably support spaced pin-point contacts 157 and 158 that are alternately engaged by contact block 155 during vibratory movement of the wire arm 154, and a conductor 159 leads from the current supply to the screw 65 which secures the U-shaped carrier to the plate 148. Thus a sensitive circuit interrupter is provided that is similar to that at the left-hand portion of the apparatus. A spring loop 160 is formed in the upper portion of the wire arm 154 70 above the disk and around this disk the wire is bent into V-shaped angular portions 161 that tangentially and frictionally seat in the edge groove of the disk. Thus the disk and arm are operated in the same manner as the structure at 75

the left-hand portion of the apparatus to alternately flash the neon gas bulbs 145 and 146 to indicate action of the respiratory system of the patient. In order to operatively connect this mechanism with the pressure-sensitive bellows z the pinion is engaged by a gear-segment 162 on the end of a strip of insulation forming a rock-lever 163 which is carried upon a rock pin 164 that has its ends mounted in the frame plates 148-149. The end of the rock-lever 163 opposite the gear-segment extends towards the block 128 where it has a slotted or forked end 165 that is engaged by a lateral pin 166 adjustably carried in the slotted projecting portion of a short plate 167 that is secured to the adjacent face of the block. Thus movement of the bellows z and its guide rod 126 is transmitted to and actuates the circuit make-and-break devices for flashing and controlling the neon gas lamps 145 and 146 to visually indicate to the physician or operator the inhalation and exhalation movements of the patient's chest.

In the present structure I provide means for taking and recording the auricular contractions and the force thereof as may be found in the jugular at the neck of the patient. The purpose of this is to ascertain auricular conditions which may be present and which may not necessarily appear in the other portions of the graph-sheet due primarily to the fact that the low pressure reading is recorded from the force of the left ventricle contraction. This structure embodies a diaphragm unit 168 the sensitive elastic element of which is provided with a horizontally disposed stud 169. The bracket which mounts the unit 168 on the plate G has a horizontal lateral extension 170 projecting from it towards the platen and at its free end it carries the pivot pin 171 of a pendent irregularly shaped pointer 172 having a pen 173 at the extremity of its laterally disposed portion extending in front of the graph-sheet, which pen is adapted for engagement with the graph-sheet. The stud 169 is operatively connected with the pointer 172 by a link 173a that is hingedly or pivotally connected at its ends to the pointer and said stud. A pipe 174 communicates with the interior chamber of the diaphragm unit and extends outside the cabinet for connection to a hose 175 leading to a pressure-sensitive tambour element 176 that is placed on the neck of the patient at the location of the jugular and is secured in position by a band or strap 177 that encompasses the patient's neck as graphically illustrated in Fig. 7.

For the purpose of providing a convenient means for simultaneously disengaging all the pointers or inscribing elements from the graph-sheet I provide a wide U-shaped rod 178 that is normally disposed back of the lower portions of said pointers close to the graph-sheet. The ends of the arms of the rod are turned laterally outwardly to provide trunnions 179 that are disposed in suitable friction bearings in the walls of the cabinet, and one of these trunnions extends through its bearing to outside the cabinet where it has a finger-grasp 180 secured to it to permit manipulation thereof so that rotation of the trunnions will swing the horizontal reach portion of the U-shaped rod outward away from the graph-sheet and move the pointers outward the desired distance from the platen. This permits easy access to the graph-sheet so that it may be severed at the end of a record and its severed edge engaged with the rewind roller 16.

In operation, the attendant applies the parts

to the patient as shown in Fig. 7, having previously lifted the pointers away from the graph-sheet, and then proceeds to inflate the air bag 115 by means of the bulb with the air control valve 119 closed against discharge of air. During this inflation stage the lamps 79-80 will alternately flash, but so soon as the brachial artery has been collapsed this alternate flashing will cease and one lamp will continue to burn alone to indicate that the critical point of high or systolic pressure has been reached. During this stage and the next succeeding step in the sequence of operation the clutch at the top of the rod 49 remains loose so that movement of the bellows z does not actuate the pointer X during the taking and recording of systolic pressure. The motor may then be switched on to move the graph-sheet, and the pointer Y released by manipulating rod 178 so that its pen will inscribe upon the chart the degree of systolic pressure in 20 millimeters, after which the motor is stopped and the pointer moved away from the graph-sheet. The attendant now releases the air control valve 119 of the bulb to permit gradual deflation of the elastic bag 115 of the arm band and at the start of and during this deflation the lamps 79-80 will again alternately flash until such time when the pressure in the elastic bag has been reduced until the heart beats in the brachial artery cease to pulsate the bellows z whereupon there is a cessation of alternate light flashes and one lamp continues to burn alone. This is an indication to the operator that the critical point of low or diastolic pressure has been reached. The clutch is then thrown in to operatively connect rod 49 with its movement amplifying means and its pointer X, and the degree of such pressure is then recorded on the graph-sheet by releasing the pointer by manipulating rod 178 and starting the motor to permit the pen to inscribe the chart for a short distance, after which the motor is stopped. The next stage is to increase pressure in the elastic bag approximately 10 mm. to 15 mm., above the diastolic critical point. The pointer X will now start an oscillatory movement, due to the pulsating pressure now in the pneumatic system, and its pen will inscribe an irregular or saw-toothlike line indicating the heart beats and disclosing characteristics thereof, during which the pointer Y will continue to trace a line on the chart to show at what pressure the heart-beats are recorded by pointer X.

During the making of the above-described records the pointer Z will continue to record the patient's respiratory actions and the pointer 172 will also record the auricular contractions and the force thereof as found at the jugular in the patient's neck. This permits the physician or diagnostician to make definite comparisons and to ascertain and note abnormalities in one graph line that may not have been recorded in one of the other graph lines.

What I claim is:

1. Apparatus of the kind described comprising a support, a low-pressure responsive device mounted thereon, said device also responsive to pulsating pressure, movement transmitting means actuated by said device, an inscribing pointer actuated by said means, a high-pressure responsive device on said support, movement transmitting means actuated by said high-pressure device, a second inscribing pointer actuated by said last-mentioned means for recording high-pressure and also the pressure at which pul-

sating pressure is recorded, a movable continuous graph-sheet cooperating with said pointers; a pressure-creating appliance applied to an artery of a patient and communicating with both 5 of said pressure-responsive devices for actuating the latter, an inherently elastic pressure-creating element applied to the chest and operated by respiratory actions of the patient, a pressure-responsive device communicating with and actuated by said respiratory element, means connected with said last-mentioned pressure-responsive device adapted to record respiratory actions 10 on said graph-sheet adjacent the arterial record whereby the separate records are disposed in coordinated relation to each other on said graph-sheet, and mechanically actuated means for advancing said graph-sheet during movements of the recording elements of the apparatus. 15

2. Apparatus of the kind described comprising 20 a plurality of pressure-responsive devices, a pressure creating appliance applied to an artery of a patient and communicating with certain of said devices whereby different degrees of pressure and pulsating pressure are adapted to be supplied to said responsive devices, an inherently elastic pressure creating element applied to the chest and affected by respiratory actions of the patient and communicating with another of said responsive devices, a pressure creating appliance 25 affected by auricular action of the patient, a plurality of movement transmitting mechanisms each operatively connected with and actuated by a pressure-responsive device, a plurality of inscribing pointers each actuated by a transmission 30 mechanism, a continuous graph-sheet common to all of said pointers, whereby the separate records inscribed by said pointers are disposed in coordinated relation to each other and the pressure at which pulsations are recorded is indicated, and mechanically actuated means for advancing said graph-sheet. 35

3. Apparatus of the kind described embodying 40 means including a closed conduit in which varying pneumatic pressures are produced, a pneumatic device communicating with said conduit and sensitive to the pressure therein, a longitudinally reciprocable rod actuated by movement 45 of said pneumatic device, a rock-spindle disposed transverse to said rod, a transverse member 50 on said rod adjacent said spindle, a lateral element on said spindle and having operative connection with said transverse member, a vibratory pointer actuated by said spindle, and a mobile chart co-acting with the free end of said pointer 55 and movable independently thereof.

4. Apparatus of the kind described embodying 60 means including a closed conduit in which varying pneumatic pressures are produced, a pneu-

matic device communicating with said conduit and sensitive to the pressure therein, a longitudinally reciprocable rod actuated by movement of said pneumatic device, a rock-spindle disposed 5 transverse to said rod, a disk on the portion of said rod adjacent said spindle, a lateral arm adjustably mounted on said spindle and having a portion engaged with a face of said disk, a pointer mounted upon and actuated by said spindle, and a mobile chart with which the free 10 end of said pointer co-acts, the movement of said chart being independent of the movement of said pointer.

5. Apparatus of the kind described embodying 15 a bellows having an anchored portion, means for creating pressure in said bellows, a rod extending from a movable portion of said bellows, a transverse member on said rod remote to said bellows, a rock-spindle disposed with its axis transverse to the axis of said rod, a lateral element 20 on said spindle that is operatively engaged with the transverse member on said rod, a mobile chart, and means carried by said spindle for indicating the movement thereof on said chart. 25

6. Apparatus of the kind described embodying 30 a bellows having an anchored portion, means for creating pressure in said bellows, a rod extending from a movable portion of said bellows, a disk on said rod having a face disposed transverse to the axis of said rod, a rock-spindle having its axis transverse to the axis of said rod, a lateral arm adjustably anchored on said spindle and having its free end contacting the said 35 transverse face of said disk, a mobile chart, and a pointer carried by said spindle and adapted for recording movements of said spindle upon said chart.

7. Apparatus of the kind described comprising 40 means including a closed conduit in which pulsating and non-pulsating pressures are produced, a pneumatic device sensitive to high-pressure and having communication with said conduit, said device being unaffected by pulsating pressure, a rock-spindle having operative connection with 45 and adapted to be actuated by said high-pressure sensitive device, a pointer-arm actuated by said rock-spindle, a mobile graph-sheet co-operating with the indicating portion of said arm, a second pneumatic device communicating with 50 said conduit, said last-named device being influenced by pulsating pressure, and an indicator operatively connected to said second pneumatic device and cooperating with said graph-sheet, whereby the first-named arm is adapted to indicate the pressure at which pulsations are indicated by the second-named arm. 55

THOMAS BRADFORD.
